(57) **CLAIM**

The ornamental design for a vacuum cleaner hose, as shown and described.

DESCRIPTION

FIG. 1 is a front, right, and top perspective view of a vacuum cleaner hose, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is a partial enlarged view of an area labeled 8 in FIG. 3 comprising a hose.

FIG. 9. is perspective view of the vacuum cleaner hose showing a status when the hose is curved.

FIG. 10 is a perspective view of the vacuum cleaner hose of FIG. 2 where in a vacuum cleaner suction head, a hose connection part, and the hose are dissembled.

FIG. 11 is a front elevation view of FIG. 10.

FIG. 12 is a rear elevation view of FIG. 10.

FIG. 13 is a left side elevation view of FIG. 10.

FIG. 14 is a right side elevation view of FIG. 10.

FIG. 15 is a top plan view of FIG. 10; and,

FIG. 16 is a bottom plan view of FIG. 10.

The broken lines shown in the drawings are included for the purpose of illustrating portions of the vacuum cleaner hose that form no part of the claimed design.

1 Claim, 16 Drawing Sheets
